UNITED STATES PATENT OFFICE.

LEWIS PATRIC, OF SPRINGFIELD, OHIO.

PUMP.

SPECIFICATION forming part of Letters Patent No. 274,965, dated April 3, 1883.

Application filed June 21, 1882. (No model.)

To all whom it may concern:

Be it known that I, LEWIS PATRIC, a citizen of the United States, residing at Springfield, in the county of Clarke and State of Ohio, have invented certain new and useful Improvements in Pumps; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to that class of iron pumps which operate both by force and by suction.

The objects of my invention are, first, to keep up a continuous flow of water from the discharge-spout; second, to produce a pump which is simple in construction and easily and cheaply made; third, which is durable and strong in its working parts; fourth, having the cylinder in which the piston works cast in such a form as to be bored out in less time and with much less expense than is done in ordinary iron-pump cylinders; fifth, having the piston-packing made adjustable by a simple device which shall keep it tight and in complete working order; sixth, having the lower valve-box made to lock into place and readily unlocked and removed when required; seventh, having the eduction-valve made with a simple device for arresting its lift at the proper point and for allowing a continuous flow of the water through the valve-chamber when it is raised to the stop-point; eighth, having the base of the pump, inclosing the rod and the stem, made so that the working parts of the pump can be easily taken out through the same, and to allow of the inspection of those parts below the platform when required; ninth, bracing the pump and its connections by a peculiar arrangement to prevent the same from being loosened by operating it.

Figure 1 is an elevation of my improved iron pump. Fig. 2 is an enlarged view of the same without the base, which is shown in Fig. 5. Fig. 3 is a longitudinal section of the operative parts of the pump below the platform. Figs. 4, 6, 7, 8, 9 are details; Fig. 10, an enlarged view of the cylinder and the parts contained therein.

A is the pump, which consists of the pipe

d, having an air-chamber, e, at the upper end, above the discharge-spout, over which is fulcrumed the handle d', to the end of which a gas-pipe pump-rod, a, is connected by a pin, 1, passing through it. The end of the pipe-rod above the pin is threaded inside for the set-screw c, which secures the pin therein and allows the rod to be easily and quickly detached, so that it can be withdrawn from the pump-cylinder b, which is shown below the platform P of the well in Fig. 1, and in the longitudinal section, Fig. 3. The cylinder b is cast in one piece, with the curved eduction-pipe leading from its interior, and the globular valve-chamber e' on it. The stalk-pipe or stem d passes down through the base B, (see Figs. 1, 5, and 6,) and is screwed into the valve-chamber e' until its end reaches the interior k. The cylinder b is cast with the circular ribs c' and c'' on the inside, as seen in Fig. 3, the object of which is to save time in boring out the cylinder to fit the brass tubular lining l, inserted therein. The boring takes place after the cylinder is cast and before the lining is inserted. It will only be necessary to smooth the ribs. By casting the ribs with the cylinder the necessity of boring out the whole inner surface is obviated, which boring would require seven or eight times the labor of simply smoothing the ribs that sustain the cylinder-lining in place equally as well as if the whole inner surface of the cylinder were entire. The object of the ribs is to save metal and labor and cost of manufacture, whereas if the ribs were not cast with the cylinder it would be necessary to cut out about seven-eighths of the metal to form them. In the figure referred to two of these rings are seen—one at the top and one near the bottom of the cylinder opposite the eduction-pipe—for the purpose of supporting the lining away from the cylinder. The two are connected by a vertical rib, c'', which is also cut with the boring-tool to the same gage with the rings c', and is intended to support the seam in the brass lining l, which is driven tightly down into the cylinder until it reaches its seat on a rib, c'', which is cast on the inside, but not bored out, this being as far down as the throw of the piston extends. The valve-box C is slightly less in diameter than the lining l, and sets in the bottom of the cylinder, where it is secured by a wire latch, s, the end of which is sprung out into

the circular recess n under the rib c'' , as seen in Fig. 3. The valve-box C in Fig. 7 is seen from the under side, with the valve shown in dotted lines. It will be seen that the wire 5 latch s is coiled at one end around a button, K' , cast on the inner depressed segment, p , of the box, its end extending from this through a notch, n' , in the side of the valve-box. It extends almost diametrically across the threaded 10 taper hole u in the segment p , the object being to allow it to be unlocked from out the groove n . (See Figs. 7, 8, and 9.) This is done by inserting a rod having a taper screw into the hole, which, as it is screwed in, pushes aside 15 the wire and unlocks it.

In Fig. 9 the operation is illustrated. The rod 6 (a broken section of which is shown) is screwed down through hole u in the segment. As it reaches the bottom of the hole it comes 20 in contact with the wire s , which it pushes to one side, thus disengaging its end from groove n under rib c'' , releasing the valve-box, which can then be easily drawn out with the rod. The depression in the top of segment p , being 25 somewhat conical and terminating in the hole u , guides the end of the rod to the hole, so that it may be readily inserted. The cylinder is smaller in diameter at the lower end, where the valve-box rests. By the arrangement de- 30 scribed a renewal of the valve can be easily made without the necessity of drawing out the pump. The valve t in the education-pipe, having its seat in the bottom of chamber e' , has a spherical end, with a belt forming a 35 shoulder on which it rests. It has a long thin upright stem, which is of nearly the same width as the caliber of the stem d , in which it fits loosely. It is grooved on either side, the groove beginning near the edge of the shoulder 40 and extending throughout its length, the object of which is to allow the water to pass by it upward when it is raised to its full height. A projecting stop, f , on each side, in line with the edge of the stem, just above the 45 head, arrests the motion of the valve at the proper point. This stop strikes the lower end of the pipe d , which extends down into the top of the valve-chamber for that purpose. The hole tapped in the latter for the pipe is 50 large enough to allow the valve to be dropped through it onto its seat. After it is inserted the end of the pipe is slipped down over its stem and screwed into its place.

The packing of piston D is made so as to be 55 easily and quickly expanded to the surface of the cylinder by simple means, which will be hereinafter described. Its rod a is of gas-pipe, with a solid end, r , on which a coarse-threaded screw is first cut, upon which a cast conical 60 nut, u' , is fitted, which forms the expander. Below this part the rod is smaller, and a finer screw-thread is cut thereon. After screwing on the conical nut to its place a washer, w' , is slipped on the end of the rod, over the smaller 65 part, and next to it a leather cup, pressed out from a single piece of sole-leather, which forms the outer packing next the cylinder-lining.

This cup has within it an elastic ring, r' , of rubber or other equivalent material, into which the conical expanding-nut u' extends. Under 70 the leather cup a washer-nut, w'' , is screwed upon the rod, tightening the inside washer, w , up against the shoulder formed by the end of the coarsely-threaded part traversed by the expander. This completes the piston. When it 75 is necessary to tighten the packing all that is required is to give the expander a slight turn downward, when it is forced into the elastic ring r' , expanding it and the leather packing l' , next the lining of the chamber. This is done 80 without removing any part of the piston from the rod and without the use of tools of any kind.

The base B, which incloses the stalk d and the rod a of the pump, is elevated somewhat 85 above the platform P, and has a main chamber for the stalk d , and a smaller one extending from and opening into the other for the rod. This latter is provided with a hinged lid, a' , to allow the pump-rod and its piston D to be 90 withdrawn from the cylinder through it without disturbing the other parts of the pump. To secure the pump firmly in its position above the platform a brace-rod, 2, of triangular shape, having its two ends riveted in the opposite 95 ends of a flat bar, 3, is used. Its upper angle is looped over an upper cut notch, o , on one side of the stalk, near the spout, (see Figs. 1 and, 2) where it is fastened by a machine-screw tapped in above it, with a washer under its 100 head overlapping the rod. The bar 3, which forms the foot-piece, is screwed down upon the platform, and a brace, 4, extending from an ear on the cylinder up to the middle of the foot-piece 3, into which it is screwed, forms the 105 bracing below the platform. These braces stand at an angle with the pump-stalk and secure it very firmly to the platform, and when necessary to remove the pump from the well are easily and quickly detached. 110

A small hole, o' , is made in the top of the air-chamber e to allow it to partially fill with water, and thus facilitate a continuous flow from the discharge-spout as the pump is operated. 115

I claim as my invention—

1. The combination, with a pump cylinder having circular ribs cast on its inner surface, of a lining having its outer circumference in contact with the ribs, for the purpose set forth. 120

2. The combination, with a pump-cylinder having circular and vertical ribs cast upon its inner side, and the vertical ribs extending from one circular rib to the other, of a lining supported by the circular ribs, and having its 125 seam parallel to and in contact with the vertical rib, for the purpose set forth.

3. The combination, with a screw-threaded rod having nuts, one of which is conical, of a packing resting upon the lower nut, and an 130 elastic packing-ring interposed between the conical nut and the outer packing, for the purpose set forth.

4. An iron-pump cylinder provided with in-

- terior circular ribs, and a vertical rib in one side connecting the same, all bored out to the same plane for supporting the ends of the lining and the seam thereof, and having a circular rib near the bottom of said chamber, left unfinished, for a seat for the lining, and to allow the latch-spring of the valve-box to catch thereunder to secure it in place, substantially as hereinbefore set forth.
- 5 10. 5. In iron pumps having a metallic lining, a cylinder provided with ribs for holding the lining away from the sides, and a rib for supporting it above the bottom, as described.
- 15 6. In a cylinder-chamber for iron pumps, a recess or groove cast in the interior of the same, near the bottom end, to receive the end of a self-locking spring thrown outward from the valve-box, substantially as shown, for the purpose set forth.
- 20 7. The combination, with a pump-cylinder having a recess near its bottom end, of a removable valve-box provided with a self-locking spring which engages with said recess in locking it into place, substantially as shown and specified.
- 25 8. A removable valve-box for pump-cylinders, provided with a segment cast in the top, having a depressed conical upper surface terminating in a hole threaded to receive a taper screw-ended rod for removing the same, and a self-locking spring extending nearly diametrically across said hole, on the under side thereof, to allow the end of the rod, when inserted, to push said spring to one side, and thereby disengage the end of the same from a recess in the pump-cylinder into which it is locked, and to allow it to be withdrawn from the cylinder by said rod, as hereinbefore set forth.
- 30 9. In a pump-cylinder for iron pumps, a removable valve-box having a spring-latch for locking it into a recess in said cylinder, and provided with means for allowing it to be unlocked and removed therefrom, as hereinbefore specified.
- 35 40 10. In an eduction-pipe for iron pumps, a globular valve-chamber provided with a round-headed drop-valve having a circular flange or shoulder resting upon the valve-seat, stops on either side to arrest its upward lift, its head grooved on either side to allow the water to pass it when lifted to its highest point, and provided with a long flat stem extending up into the stalk-tube, nearly equal in width to the latter, to cause it to retain its perpendicularity and to wear true in its seat, as set forth.
- 45 50 55 11. In valves for iron pumps wherein the stalk-pipe enters the valve-chamber and is flush with the interior thereof, the combination, with said stalk-pipe and valve-chamber, of a drop-valve the stem of which extends into said stalk-pipe, and is provided with stops thereon which contact with the end of the stalk-pipe, arresting the upward movement of said valve and allowing the water to pass it readily from either side of the downward stroke of the piston.
- 60 12. In iron pumps, the combination, with the cylinder *b* and its several operative parts, of the eduction-pipe having valve-chamber *b'*, valve *t*, provided with stops *f*, and pipe *d*, as and for the purpose hereinbefore set forth.
- 65 13. In valve-chambers for the eduction-pipe of iron pumps, a hole for the insertion of the stalk-pipe connected therewith, bored through the top of the valve-chamber, of the size of the exterior of the pipe, to the interior, to allow the end to extend into said hole flush with the inner surface of the chamber, to allow the head of the valve to drop through to its seat below, and for said pipe end to form the means for arresting the upward lift of the valve, as set forth.
- 70 14. In iron pumps with the cylinder below the platform, a rod connecting said cylinder with the foot-piece of a triangular brace having its loop end at the top hooked over a notch or shoulder on the stalk and held in its place by a machine-bolt and washer, as hereinbefore specified.
- 75 15. A base for iron pumps for securing the same to the platform, inclosing both the stalk-tube and the pump-rod, having an opening in the top provided with a hinged lid to allow the pump-rod and the piston attached thereto to be withdrawn through it, as and for the purpose hereinbefore set forth.
- 80 85 16. In iron pumps, a piston-rod, of gas-pipe, having its upper end threaded inside, and a set-screw inserted therein, having its bearing upon the pin connecting it with the handle, to make it easily detachable and to allow the pin, when worn, to be adjusted, as hereinbefore set forth.

In testimony whereof I affix my signature in presence of two witnesses.

LEWIS PATRIC.
